Specification for Design.

Patented Apr. 8, 1919.

Application filed January 22, 1918. Serial No. 213,254. Term of patent 7 years.

To all whom it may concern:

Be it known that we, CHARLES F. L. KAUFMANN and WALLER L. KAUFMANN, citizens of the United States, residing at Santa Ana, in the county of Orange and State of California, have invented a new, original, and ornamental Design for a Vehicle-Lamp Casing and Handle-Stem, of which the following is a specification, reference being had to the accompanying drawing, forming part thereof.

Figure 1 is a rear view of the vehicle lamp casing and handle stem, showing our new design.

Fig. 2 is a side elevation thereof.

We claim:

The ornamental design for a vehicle lamp casing and handle stem, as shown.

CHARLES F. L. KAUFMANN.
WALLER L. KAUFMANN.
